Orell Wright, Spindale, N. C., assignor to
Charles Rosenstein, Paterson, N. J.

Application January 4, 1950, Serial No. 136,734

4 Claims. (Cl. 139—336)

1

My invention relates to looms and more particularly to control mechanism effective for preventing so-called "shuttle" smashes" which are usually occasioned by misalignment of the shuttle boxes relative to the race or each other.

One of the objects of my invention is to provide mechanism effective, during operation of the loom, for precluding shuttle operation upon failure of the shuttle boxes to obtain preestablished positions.

Another object of my invention is to provide electrically actuated means or mechanism of the foregoing described character which may be readily applied to looms already in use without appreciable modification.

An important object of my invention is to provide means or mechanism of the foregoing described character which is simple in construction, durable in use, efficient in operation and economical in manufacture.

With the above and other objects in view, as will hereinafter appear, the invention consists in the combination and arrangement of parts hereinafter set forth and illustrated in the accompanying drawings from which the several features of the invention and the advantages attained thereby will be readily understood by those skilled in the art.

Referring to the drawings wherein like reference characters designate like parts throughout the several views:

Figure 1 is a front elevation of a loom having my invention applied thereto.

Figure 2 is a detail sectional perspective view of the stop motion of a loom and illustrating the solenoid which is actuated to preclude shuttle operation and which view is taken substantially on the line 2—2 of Figure 1.

Figure 3 is a fragmentary perspective view of a shuttle box and guide to which my invention is applied.

Figure 4 is a detail sectional view taken on the line 4—4 of Figure 1.

Figure 5 is a diagram illustrating the electrical circuit employed.

As diagrammatically illustrated in Figure 1 of the drawings, there is provided a loom 5, of ordinary construction, equipped with the usual lay 6 having a shuttle race 7 over which the shuttle 8 is operated from and to shuttle boxes 9 and 10 disposed at the sinistral and dextral ends, respectively, of the lay 6. Each of the shuttle boxes 9 and 10 are provided with a quaternary of compartments or cells 11, 12, 13 and 14 arranged one below the other, respectively, it being understood

2

that a shuttle is projected from the cell of one box into a cell of the other box and that the boxes are vertically shifted by a box change motion 15 in accordance with a predetermined plan to obtain various cell alignments whereby a plurality of shuttles may be utilized to secure a desired weaving pattern. Each of the boxes 9 and 10 are shiftably mounted within outer and inner end guides 16 and 17, respectively, with the inner end guide constituting a part of or connected to an adjacent side frame member 18 of the loom while the outer end guide 16 is secured to a bracket 19 connected at its base to the loom frame member.

The loom is also equipped with the usual stop motion comprising a lower or cam shaft 20 provided with a cam 21 having tracking engagement with one end 22 of a cam arm 23 for oscillating the latter. The opposite end 24 of the cam arm is formed with a finger 25 terminating in a tang 26 and, below the finger, is pivoted, as at 27, to a plate 28 having mounted thereon a solenoid 29 provided with a piston 30 carrying a pin 31 extending through an elongated slot 32 formed in one end of a link 33 pivotally connected to and adjacent the pivoted end of a lever 34 constituting a component of a clutch operating mechanism 35. The lever 34 serves to effect operation of the mechanism 35 which includes a clutch operating rod 36 for actuating the clutch of the stop motion and which clutch, as is well-known in the art, functions to connect and disconnect the loom from its power source when shifted to "in" and "out" positions, respectively, by the rod 36. When the clutch is in its "in" position and the loom operating, the link 33 is in the position shown in Figure 2 of the drawings. However, by manual operation of one of the levers or handles 37 of the mechanism 35, the link 33 may be shifted to dispose its free end in close proximity to the finger 25 for engagement with the latter occasioned by oscillation of the arm 23 whereupon the link 33 functions to pivot the lever 34 with the result that the clutch rod 36 is actuated and the clutch shifted to its "out" position, thus, disconnecting the power source from the loom and stopping the latter. However, the solenoid 29 may be energized to dispose the free end of the link 33 into the path of the tang 26; thus, when the tang 26 engages the free end of the link 33, the clutch is shifted to "out" position, through the medium of the lever 34 and rod 36 as described, to effect stopping of the loom, it being understood that the solenoid 29 is connected in circuit with the feeler motion drop wires and/or devices of the loom in the usual manner and for well-known purposes.

In practicing my invention, I secure a relatively narrow and elongated strip or plate 50 of insulating material to each of the outer guides 16 in any suitable manner and which plate has embedded in its front face thereof, a vertical row of spaced contact discs 51, the latter, in the present instance, numbering eight with the discs being equally spaced on each side of the horizontal center of a cell of the adjacent shuttle box when the latter is properly positioned for shuttle operation relative to the race. The front face of the guide 16, on which the plate 50 is secured, is provided with a longitudinally extending slot 52 in which is disposed a pair of lead wires 53 and 54 extending along the rear face of the plate.

As illustrated in Figure 5, the wire 53 is connected, through the rear of the plate, to each alternate disc of the row while the wire 54 is similarly connected to the remaining discs. The wires 53 lead from the discs 51 and are connected to a common ground G while the wires 54, which also lead from the discs 51, are connected to a wire 55 which, as is well-known in the art, leads from a terminal of the aforementioned feeler motion, drop wires and/or other devices to one terminal or source 56 of electrical energy. The other terminal of the source 56 is connected to one terminal of the solenoid 29 by a wire 57 while the other terminal of the solenoid is connected to the ground G by a connection 58, the opposite terminals of the feeler motion, drop wires and/or devices being also grounded.

Each of the shuttle boxes 9 and 10, adjacent the top cell 11 thereof, has secured to its front face one end of a somewhat Z-shaped arm 60, 35 the other end of the arm extending over the plate 50 and having secured thereto a bar 61 of insulating material. The bar has fixed thereto a terminal member 62 forming part of a U-shaped bracket 63 in which is rotatably mounted a roller 64 having electrical engagement with the member 62 through the bracket 63. The roller 64 is arranged for tracking engagement over a vertical path on the plate 50 and in which path are disposed the contact discs 51 with the outer radial faces of the discs being disposed in flush relation with the front face of the plate 50. The terminal members 62 are connected together by a bridging wire 65 forming a part of the circuit in which the solenoid 29 is connected for operation with respect to precluding shuttle smashes as hereinafter made apparent.

During normal operation of the loom, the shuttle boxes 9 and 10 are shifted vertically and in unison to maintain the cells 11 to 14 inclusive of one box in aligned relation with the cells 11 to 14 inclusive of the other box, respectively, and to effect alignment of a pair of the cells, for instance, cells 11, with the race 7 whereby the shuttle 8 may be projected out of one cell 11 by the picker stick, across the race, and into the other cell 11. When the shuttleboxes are shifted in unison, the rollers 64 engage a disc 51 on each plate and which pair of discs thus engaged, are either connected to the wires 53 or to the wires 54 with the result that the circuit is not closed and the solenoid 29 remains deenergized. However, if by faulty operation of the box change motion or otherwise, the shuttle boxes are relatively shifted, the rollers 64 will engage a pair of the discs which are connected to the wires 53 and 54, respectively, as illustrated in dotted lines in Figure 5, thereby closing the circuit and effecting energization of the solenoid 29. When the solenoid 29 is thus energized, the link 33 is raised

by the piston 30 and pin 31 and with its free end disposed in the path of the tang 26, whereby the latter, due to the oscillation of the arm 23, engages and operates the link to shift the lever 34 and actuate the clutch rod 36 through the mechanism 35. When the rod 36 is thus actuated, the clutch is operated to its "out" position to disconnect the power source from the loom whereby the latter is stopped.

When the loom has thus been stopped, it necessarily follows that necessary adjustments or repairs will have to be made to effect operation of the shuttle boxes in unison before the loom may be again operated in conjunction with my invention.

It is to be noted and understood that the stopping of the loom occurs before any operation of the picker sticks is effected thus rendering the sticks inoperative for projecting shuttles from the cells. As herein disclosed, it will be apparent that the present invention provides effective means for preventing shuttle smashes occasioned by misalignment of the cells of the shuttle boxes, and that the invention may be incorporated in looms already in use without appreciable modification.

Without further elaboration, the foregoing will so fully explain the invention that others may, by applying current knowledge, readily adapt the same for use under various conditions of service. Moreover, it is not indispensable that all the features of the invention be used conjointly since they may be employed advantageously in various combinations and subcombinations.

It is obvious that the invention is not confined to the herein-described use therefore as it may be utilized for any purpose to which it is adaptable. It is therefore to be understood that the invention is not limited to the specific construction as illustrated and described, as the same is only illustrative of the principles involved which are capable of extended application in various forms, and the invention comprehends all construction within the scope of the appended claims.

What I claim is:

1. In combination, a loom having shuttle boxes shiftable in unison within guides and relative to a shuttle race between said boxes to effect pre-established shuttle operation over said race; a stop motion for arresting operation of said loom and including a solenoid for rendering said stop motion effective, and control means correlated with said boxes and including an electrical circuit connected to said solenoid and energizable upon relative shifting of said boxes for rendering said solenoid effective, said control means including contact members carried by said boxes and guides and connected within said circuit and with the members carried by said boxes being engageable with the members carried by said guides for closing said circuit upon relative shifting of said boxes for energizing and rendering said solenoid effective.

2. In combination, a loom having shuttle boxes shiftable in unison relative to a shuttle race between said boxes to effect pre-established shuttle operation over said race; an electrically operated stop motion for arresting operation of said loom and including a solenoid for rendering said stop motion effective, and control means correlated with said boxes and including an electrical circuit connected to said solenoid, electrical contact means mounted on said loom, and electrical contact means mounted on said boxes and movable therewith and relative to said first mentioned

contact means, said first and second mentioned contact means being connected within said circuit and engageable with each other upon relative shifting of said boxes for closing said circuit and rendering said solenoid effective.

3. In combination, a loom having shuttle boxes shiftable in unison relative to a shuttle race between said boxes to effect preestablished shuttle operation over said race; an electrically operated stop motion for arresting operation of said loom and including a solenoid for rendering said stop motion effective; and control means correlated with said boxes and including an electrical circuit connected to said solenoid, electrical contact means mounted on said loom, and electrical contact means mounted on said boxes and movable therewith and relative to said first mentioned contact means, said first and second mentioned contact means being connected within said circuit and engageable with each other upon relative shifting of said boxes for closing said circuit and rendering said solenoid effective, one of said contact means comprising a pair of plates each constructed of insulating material and provided with a row of spaced contact discs with alternate discs of the row being connected to one side of said circuit and the remaining discs of the row being connected to the other side of said circuit, said other contact means including a pair of rollers electrically connected together for tracking engagement over said discs upon shifting of said boxes.

4. In combination, a loom having shuttle boxes

arranged at the ends of a shuttle race, respectively, and in preestablished operating positions with said race to effect shuttle operation over said race with said boxes being shiftable in unison into other preestablished operating positions relative to said race to effect said shuttle operation; a stop motion for arresting operation of said loom and including an electrically actuated device for rendering said stop motion effective; and control means correlated with said boxes and including an electrical circuit connecting said device to a source of electrical energy, and electrical contact members connected within said circuit and mounted on said boxes and said loom, respectively, and with contact members mounted on said boxes and said loom being movable into circuit closing engagement with each other by any one of the boxes when disposed out of its operating position at one end of said race and shifted out of unison with a box at the opposite end of said race whereby to close said circuit and render said device effective.
